UNITED STATES PATENT OFFICE.

OLIVER LA VALLEE AND ODILON LEMELIN, OF NEW BRITAIN, CONNECTICUT.

OVERFLOW ALARM.

Application filed January 7, 1928. Serial No. 245,169.

Our invention relates to overflow alarms for drip pans for ice boxes and has for an object to provide a device of this character adapted for attachment to the ice box or refrigerator in a convenient manner and operated through a float arranged within the drip pan of the ice box whereby to indicate at all times the amount of water within the drip pan, said float also being operatively connected with a balance weight adapted through its actuation to sound an audible alarm upon the raising of the float to a predetermined level.

A further object of the invention is to arrange the weight in a normally idle position and operatively connected with the float so as to initially cause the movement of the weight upon the raising of the float to a predetermined level, the subsequent movement of the weight being then utilized to simultaneously sound an audible alarm and also to entirely raise the float out of its operating position within the drip pan so as to permit the ready removal of the pan for emptying the water without interference from the float.

A still further object of the invention is to provide a mechanism of the above character which is adapted for attachment to the outside of the ice box or refrigerator and provided with a gauge operable through the movement of the float and positioned adjacent the upper edge of the ice box and adapted during its registering movement to appear above the upper edge of the ice box and cooperating therewith to indicate the level of the water within the drip pan.

A still further object is to provide an apparatus of this character of simple and practical construction, which is efficient and reliable in performance, relatively inexpensive to manufacture and install and otherwise well adapted to the purposes for which the same is intended.

Other objects and advantages reside in the special construction and combination of the various elements comprising the invention, reference being had to the accompanying drawings forming a part hereof, where in:

Figure 1 is a rear elevational view of an ice box showing our invention in operative position with respect thereto,

Figure 2 is a fragmentary vertical sec-

tional view taken substantially along a line 55 2-2 of Figure 1,

Figure 3 is a transverse sectional view taken along a line 3-3 of Figure 1 and illustrating a plan view of the drip pan with the float arranged therein,

Figure 4 is a detail of the level gauge, and

Figure 5 is a vertical sectional view taken along a line 5-5 of Figure 1.

Referring now to the drawings in detail, we have shown our invention adapted for use upon an ice box or refrigerator of the conventional type illustrated generally at 5 and beneath which is arranged the drip pan 6 immediately beneath the overflow pipe 7 of the ice box. Within the pan is disposed one or more floats 8 secured to one end of an arm 9 extending horizontally beneath the ice box toward the outer edge thereof and pivotally mounted intermediate its ends upon a bracket 10 secured to the bottom 75 of the ice box.

The outer end of the arm 9 is attached to a vertically disposed rod 11 carried for vertically sliding movement within brackets 12 attached to one of the walls of the ice box, the upper end of the rod extending outwardly from the ice box at right angles and inserted within a slotted opening 14 formed at one end of a link 15 pivotally mounted intermediate its ends upon a bracket 15' attached to the ice box and with its opposite ends attached to an upwardly extending gauge 16. The gauge 16 is mounted for sliding movement within a glass tube 17 secured by a bracket 18 to the wall of the ice box and with its upper end extending slightly above the upper edge of the box. The portion of the glass tube protruding above the upper edge of the ice box is marked with a scale indicated at 19 corresponding to the various levels of the water in the drip pan 6. As will be seen from an inspection of Figure 1 of the drawings the upper end of the gauge 16 is normally disposed substantially at a horizontal plane with the upper edge of the ice box when the water in the drip pan is at its lowest level and upon the raising of the float it is apparent that the gauge 16 will be moved upwardly within the tube 17 so that the upper edge of the gauge will register in a proper manner with the scale 19 provided thereon. The gauge 16 may be painted in a contrasting color so that the

same will appear through the glass tube 17 in a prominent manner.

The bracket 15' is provided with a horizontal extension 20 upon the outer end of which is arranged a pivot pin 21 and upon which pin is mounted a bell crank 22 having one of its arms extending upwardly with its upper end provided with a weight 23 normally secured in an upwardly extended position by a friction gripping spring 24 attached to the wall of the ice box, the opposite arm of the bell crank being normally horizontally disposed with its outer end provided with an adjustable trip 25 disposed immediately beneath the angular extension 13 on the upper end of the rod 11.

A bell 26 is also secured to the wall of the ice box with its sounding arm 27 extending within the path of the downward movement of the free end of the link 15 and engageable thereby so as to cause the actuation of the arm 27 to sound the bell. The spring 28 is attached to the arm 27 operating to normally retain the arm in position for engagement with the end of the link 15. The trip 25 is attached to the bell crank 22 by means of an adjusting screw 29 so as to enable the trip to be adjustably spaced with respect to the angular extension 13 so as to permit a predetermined movement of the link 15 in advance of its engagement with the trip. Thus during the initial raising movement of the float 8 the trip and its associated parts are unaffected, the gauge 16 being provided for indicating the various positions in the float up to a point approximating a high level of the water within the drip pan. As soon as the float reaches a predetermined level and the upper end 13 of the rod is lowered a corresponding extent, the same will engage the trip 25 and through its connection with the bell crank 22 will throw the weight 23 off balance and cause the same to swing downwardly in a direction toward the angular upper end 13 of the rod which thereby will cause the rod 11 to move downwardly to its fullest extent and thus entirely raise the float 8 from its position in the drip pan. The downward movement of the rod 11 will also cause the engagement of the end of the link 15 with the sounding arm of the bell so as to cause the actuation thereof.

It will be apparent that by the removal of the float 8 from the drip pan that the latter may be easily and conveniently removed for emptying the contents of the water without the float interfering with the removal thereof.

If desired an adjustable weight 30 may be slidably mounted on the arm 9 carrying the float so as to enable a proper balance to be maintained between the float and the mechanism connected therewith.

It is obvious that the invention is sus-

ceptible of various changes and modifications, without departing from the spirit or scope of the invention or sacrificing any of its advantages, and we accordingly claim all such forms of the device to which we are entitled.

Having thus described our invention, what we claim as new is:

1. In a liquid level indicator of the class described comprising a float arranged within a liquid container, a gauge operatively connected therewith and adapted to register the movements of the float, an alarm actuated at a predetermined period of movement of the float and means actuated by the movement of the float to a predetermined level for removing said float from said container.

2. In a liquid level indicator of the class described comprising a container having a float arranged therein, a gauge operatively connected with the float for registering the extent of movement thereof, a weight normally disengaged from said float and arranged for connection therewith upon the raising of the same to a predetermined level and adapted through such engagement to remove the float from said container and an alarm arranged for actuation upon the removal of the float.

3. In a liquid level indicator of the class described comprising a liquid container having a float arranged therein, a level indicator, means connecting the same for actuation by the movement of the float, a poised weight normally inactive during the initial movement of the float, trip means actuated through said first named means for releasing said weight for engagement therewith thereby to remove the float from the container and an alarm arranged for actuation upon the movement resulting from said weight.

4. A level indicator for the drip pan of a refrigerator comprising a vertically disposed rod slidably mounted upon one of the walls of the refrigerator, a pivotally mounted arm having one end attached to the lower end of said rod with a float mounted at its opposite end and arranged within the drip pan, said rod having its upper end terminating in an angular extension, a link pivotally attached to the refrigerator having a slotted opening in one end for receiving said extension, a vertically movable indicator attached to the opposite end of the link and manually disposed with its upper end adjacent the upper edge of the refrigerator, said indicator being slidably arranged within a transparent tube having a scale cooperating with the upper end of the indicator, a pivotally mounted bell crank having one of its arms extending vertically with a poised weight carried thereby and the other of its arms disposed horizontally and provided with an adjust-

able trip engageable by said angular extension for releasing said weight upon the movement of the rod a predetermined extent, said angular extension being disposed in the path of said weight and responsive to the force thereof whereby to remove the float from said container and an alarm ar-

ranged for actuation upon the movement of said weight.

In testimony whereof we affix our signatures.

OLIVER LA VALLEE.
ODILON LEMELIN.
